US00D872725S

(12) **United States Design Patent** (10) **Patent No.:** **US D872,725 S**
(45) **Date of Patent:** **** Jan. 14, 2020**

(54) **TELEPHONE HEADSET HOLDER**
(71) Applicant: **RTX A/S**, Nørresundby (DK)
(72) Inventor: **Jens Christian Lindof**, Nørresundby (DK)
(73) Assignee: **RTX A/S**, Nørresundby (DK)
(**) Term: **15 Years**
(21) Appl. No.: **29/627,278**
(22) Filed: **Nov. 24, 2017**

(30) **Foreign Application Priority Data**

May 24, 2017 (EM) 004015972

(57) **CLAIM**

The ornamental design for a telephone headset holder, as shown and described.

DESCRIPTION

FIG. 1 is a perspective view of a telephone headset holder according to the principles of the present invention; FIG. 2 is a front elevational view thereof; FIG. 3 is a rear elevational view thereof; FIG. 4 is a left side elevational view thereof; FIG. 5 is a right side elevational view thereof; FIG. 6 is a top plan view thereof; and, FIG. 7 is a rear perspective view thereof. The broken lines depict portions of the article that form no part of the claimed design.

1 Claim, 7 Drawing Sheets
